US0D1014463S

(12) **United States Design Patent** (10) **Patent No.:** **US D1,014,463 S**
(45) **Date of Patent:** **** Feb. 13, 2024**

(54) **HEADSET**

(71) Applicant: **Changmao Li**, Shenzhen (CN)

(72) Inventor: **Changmao Li**, Shenzhen (CN)

(**) Term: **15 Years**

(21) Appl. No.: **29/821,055**

(22) Filed: **Dec. 27, 2021**

(51) LOC (14) Cl. **14-01**

(52) U.S. Cl.

USPC **D14/206**; D14/226

(58) **Field of Classification Search**

USPC D14/206, 226, 205, 225; D29/112; 2/209; 362/105; 381/380–381, 370, 374

(57) **CLAIM**

The ornamental design for a headset, as shown and described.

DESCRIPTION

FIG. 1 is a front, right side, top perspective view of a headset showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict portions of the headset that form no part of the claimed design.

1 Claim, 7 Drawing Sheets
